(57) **CLAIM**

The ornamental design for a display screen or portion thereof with graphical user interface, as shown and described.

DESCRIPTION

FIG. 1 is a front view of a display screen or portion thereof with graphical user interface showing our new design; FIG. 2 is a front view of a second embodiment thereof; FIG. 3 is a front view of a third embodiment thereof; FIG. 4 is a front view of a fourth embodiment thereof; FIG. 5 is a front view of a fifth embodiment thereof; and, FIG. 6 is a front view of a sixth embodiment thereof.

The dashed broken lines in the Figures show a display screen or portion thereof, and form no part of the claimed design. The dot-dash broken lines in the Figures and the areas within the dot-dash broken lines show portions of the graphical user interface that form no part of the claimed design.

1 Claim, 6 Drawing Sheets
